UNITED STATES PATENT OFFICE.

GEORGE FOSTER REZNOR, OF MERCER, PENNSYLVANIA.

RADIANT STOVE.

Application filed July 5, 1923. Serial No. 649,695.

To all whom it may concern:

Be it known that I, GEORGE FOSTER REZNOR, a citizen of the United States, residing at Mercer, in the county of Mercer and State 5 of Pennsylvania, have invented new and useful Improvements in Radiant Stoves, of which the following is a specification.

My invention relates to radiant stoves.

One object of this invention is to provide 10 a radiant stove or fireplace which is attractive in appearance, simple in construction, easily repaired, and relatively cheap to manufacture. Another object is to provide a novel mounting for the back wall whereby 15 it may be readily inserted and removed without the use of special fastening devices. I provide also novel means for holding the radiants vertically and for preventing the overheating of the wall of a room close to 20 the back of the stove. I provide also a novel means for mounting the mixing tube so that by the removal of a single screw or bolt the burner tubes together with the mixing chamber carrying the same may be readily removed. Other objects appear hereinafter.

Referring to the accompanying drawings, Fig. 1 is a front view of one form of my invention, the radiants on the right-hand side being omitted; Fig. 2, a section taken 25 on the line II—II of Fig. 1; Fig. 3, a fragmentary view showing the right-hand parts in front elevation and the left-hand parts in vertical section; Fig. 4, a plan view of Fig. 1 with the hood omitted and the back 30 plate or jacket in horizontal section; Fig. 5, a section on the line V—V of Fig. 4, back wall omitted; Fig. 6, a sectional detail showing the manner of mounting one of the front legs; Fig. 7, a detail view showing 35 the manner of supporting the right-hand end of the mixing tube; Fig. 8, a bottom plan view of the hood; Fig. 9, an end view of the hood; Fig. 10, a fragmentary elevation of the back wall; Fig. 11, a vertical 40 section through the back wall and one of the radiants; Fig. 12, an enlarged front elevation of one of the radiants.

On the drawings, 1 and 2 represent 45 respectively front and rear metallic frame members, the front member comprising a horizontal plate of metal with rearward flanges 3 and 4 at its edges. The ends 5 of the frame member 1 curve forwardly and terminate in the flanges 6 parallel with the front of the stove. To the front of each flange 6 is secured by a single screw 8 the

upper vertical member 9 of a leg 10 having two spaced feet 11, the screw extending through the flange 6 and into the leg-member 10 and serving as a pivot on which the leg may adjust itself so that both feet 11 will rest on an uneven tiled hearth, floor or other support.

The rear frame member 2 comprises a casting 12 and a pair of hollow posts or columns 13 secured to the ends of the casting by screws 15, which extend through the end walls 17 of the casting and into lugs 16 integral with the inner face of the legs. The columns are flush with the ends of the casting 12. The frame member 2 has the forwardly projecting end portions 18 (only one shown) having each a flange 19 (only one shown), through which a screw 20 passes into a boss 21 on the inner face of the frame member 1. The rear wall 22 of the frame member 2 has the leg 23 secured thereto by the bolts 24.

The top wall of the frame member 2 has a series of openings 25 and is elevated somewhat above the upper edge of the member 1, the upper edges 26 (only one shown) of the projecting portions of the member 2 being inclined downwardly to meet the upper edge of the member 1. A metal cover plate 27 extends from the forward faces of the columns 13 and the upwardly extending flange 28 just in front of the openings 25, down over the upper edge of the frame member 1, and its ends reach about to the beginning of the curved portions 5.

The bracket 29 is secured to the back wall 22 by the screws 30 and has the lug 31 which carries the gas jet or nozzle 32, which projects into the air mixing tube 33, having on its upper face the gas jets or burners 34 which project into the openings 25. The latter are of such size as to allow the tube 33 to be moved slightly longitudinally. The lower side of the upper member 35 of the tube 33 has a thin depending lug or leg 36 which rests on the upper edge of the bracket 29, a finger 37 depending from the leg 36 and engaging the inner face of the bracket to limit the movement of the mixer tube toward the right on Fig. 5. When the leg is on the bracket and the finger is against the bracket, the tube 33 is properly positioned so as to have the jets 34 rightly placed in the openings 25, and a screw 38 is passed through the left-hand column 13 and screwed through the adjacent member 17 of

the frame and against the end of a socket 39 in the end of the tube 33 as shown in Fig. 5. The screw supports the adjacent end of the mixer tube and also holds it in its normal position. By removing the screw, the mixer tube with the burners may be readily removed. 41 is the gas-valve for the nozzle 32, and 40 is the usual hand shaft for operating the valve.

10 The columns 13 have their opposing faces open and their tops are closed by the removable caps 42 secured in place by the screws 43. The vertical hollow spaces in the columns are guides and retaining members for the back-wall 44 and the hood 45, composed of any highly refractory material suitable for the purpose required. This material may be fire-clay or other compositions well known for the purpose intended. 15 The back-wall has end portions 46 which slide down in the columns. The main portion of the back-wall stands back somewhat from the guide portions 46 so that its front face is slightly back of the openings 25. 20 This front face carries a number of vertical ribs 47, one back of the center of each opening 25, and also other vertical ribs 48 between adjacent ribs 47.

I provide a number of vertical radiants 49, each hollow and provided with a number of openings 50. The radiants are open at their lower ends, one radiant being seated over each opening 25. Each radiant has a vertical recess 51 in its back to receive one of the ribs 47. The upper part of the front face of the back-wall 44 slants upwardly and rearwardly and the tops of the radiants stand opposite this slanting part and are provided with closed tops, but their rear walls are provided each with an opening or vent 52 through which the heat and products of combustion pass on their way to the notch 53 in the top of the back-wall. The ribs 48 provide ventilation between the radiants and the back-wall 44.

45 The hood 45 rests upon the upper edge of the back-wall 44 and has end guiding lugs 54 slidable in the columns 13. The front of the hood lies in front of the upper ends 50 of the radiants and is recessed to receive and retain the said ends, and to form a flue in connection with the said slanting part of the back wall for the conduction of waste gases and heat to the rear vent comprising the registering recesses 53 and 56 in the back-wall and the rear face of the hood. The back-wall is seated in front of a retaining flange 57 on the top of the frame member 2.

50 58 is a sheet-metal jacket having its upper end flanged and seated in a recess 59 in the hood. The side edges of the jacket are seated in the columns just back of the lugs 46 and 54. The jacket is spaced from the rear face of the back-wall and the hood and

is open at the bottom and provided with several holes 60. A pipe connection 61 is secured in the jacket opposite the vent 53—56, whereby the waste gases may be connected to a chimney by suitable lengths of pipe. The jacket provides for a circulation of air so that the stove may be set close to a house-wall without danger of setting fire to the latter.

55 The caps 42 have holes 62 in their inner faces, into which a fire-screen may be secured by means of projections on the screen extending into the holes.

I claim—

1. In a radiant stove, a frame, a mixer 80 tube having a depending supporting leg for one end of the tube, a support for the leg, carried by the frame, a finger carried by the tube for limiting the movement of the tube in one direction, and a screw supporting the remaining end of the tube and limiting the movement of the tube in the opposite direction.

2. In a radiant stove, a frame, a mixer tube, a screw supporting one end of the 90 tube and movable in one direction to hold the tube at one position and in the opposite direction to allow the tube to be moved from said position, a support for the remaining end of the tube, and means for preventing longitudinal movement of the tube when the screw is holding the tube in the said position, the support being sufficiently short to release the said remaining end of the tube when the screw has been backed off a short distance.

3. In a radiant stove, a refractory back-wall, radiants in front thereof, interfitting projections and depressions on the opposing faces of the back-wall and the radiants for interlocking the radiants and the back-wall to prevent the radiants from moving laterally, and vertical grooves between the back-wall and radiants to afford ventilation between the same.

4. In a radiant stove, a frame, two hollow columns supported thereby and open at their opposing faces, a back-wall having end portions in the columns, a separable hood having end portions in the columns and resting on the back-wall, and caps secured to the tops of the columns and overlying the said end portions of the back-wall.

5. In a radiant stove, a frame, a vertical column at each end, the columns having their opposing faces provided with vertical slots, a refractory back-wall having end portions in the slots, radiants retained at the front face of the back-wall, and a flue wall spaced from the rear face of the back-wall and having its ends seated in the said slots and retained thereby.

6. In a radiant stove, a frame, a vertical column at each end, the columns having

- their opposing faces provided with vertical slots, a refractory back-wall having end portions in the slots, radiants retained at the front face of the back-wall, and a flue wall spaced from the rear face of the back-wall and having its ends seated in the said slots and retained thereby and loosely supported by the frame.
7. In a radiant stove, a frame, a vertical column at each end, the columns having their opposing faces provided with vertical
- slots, a refractory back-wall having end portions in the slots, radiants retained at the front face of the back-wall, a flue wall spaced from the rear face of the back-wall ¹⁵ and having its ends seated in the said slots and retained thereby, and a pipe connection carried by the flue-wall.

In testimony whereof, I hereunto affix my signature this 30th day of June, 1923.

GEORGE FOSTER REZNOR.
